UNITED STATES PATENT OFFICE.

ALBERT S. COLE, OF LIVERMORE, CALIFORNIA, ASSIGNOR TO COAST MANUFACTURING AND SUPPLY COMPANY, OF LIVERMORE, CALIFORNIA, A CORPORATION OF DELAWARE.

PORTABLE ELECTRIC FUSE-LIGHTER.

1,262,307.

Specification of Letters Patent. Patented Apr. 9, 1918.

Application filed May 23, 1916. Serial No. 99,319.

To all whom it may concern:

Be it known that I, ALBERT S. COLE, a citizen of the United States, residing at Livermore, in the county of Alameda and 5 State of California, have invented certain new and useful Improvements in Portable Electric Fuse-Lighters; and I hereby declare that the following is a full, clear, and exact description thereof, reference being 10 had to the accompanying drawings, which form part of this specification.

This invention is a novel portable electrical apparatus for igniting fuse, which I call a portable electric fuse lighter, and is 15 especially designed for igniting or "setting off" fuse in mines, quarries and other places where fuses are used.

The object of the invention is to provide an apparatus that can be conveniently carried by a miner or other person, and which 20 comprises an electric battery, current amplifying devices, and spark producing devices, by which the miner can ignite an ordinary powder fuse when desired, without 25 danger to himself. The apparatus is so constructed that it will produce a stream of electric sparks by simply pressing a key; and such fuse lighter can be readily carried to any part of a mine; and is self contained, 30 and independent of any wall conductors, and does not have to be plugged into a socket or connected with extraneous electrical conductors; and the igniting operations of the lighter may be controlled by 35 one hand.

A practical embodiment of the invention is illustrated in the accompanying drawings, and the invention consists in the novel construction combination and arrangements of elements hereinafter described and 40 particularly set forth in the appended claims.

In said drawings:

Figure 1 is a perspective view of the complete apparatus.

Fig. 2 is an enlarged sectional view thereof partly in diagram.

Fig. 3 is an end view of the igniter.

Explaining the construction shown; 1 50 designates a portable holder, preferably constructed of leather, and having a shoulder strap 1^a whereby it can be conveniently suspended on a person. The holder is designed to contain batteries 2, preferably dry 55 batteries, a transformer 3, and a condenser

4, all of which may be of any suitable construction, and are assembled in the casing in compact order.

The igniter proper is electrically connected with the electrical devices in the 60 holder, and the operative parts of the igniter are preferably mounted in or on a casing; preferably composed of a cylindric body 8 formed of insulating material or fiber, and closed at its ends by plugs 8^a and 65 8^b preferably of hard rubber. The plug 8^a is provided with two parallel longitudinal bores in which are secured tubes 8^c, which may be of brass, and in these tubes are mounted the sparking terminals or members 70 9, 9^a which are made of suitable metal and their outer ends are bent inward toward each other; and their points almost contact but are separated sufficiently to produce the proper desired spark gap. These members 75 9, 9^a can be adjustably secured in the tubes 8^c by screws 8^d or other suitable manner; and are connected with the sources of electricity and with a circuit closer as herein-after explained.

Short circuiting or sparking between the tubes 8^c or members 9, 9^a is prevented by means of a projecting rib 8^e on the plug 8^a, which rib extends between said tubes 8^c and toward the points of the members as shown 85 in the drawings. It will be observed by reference to Fig. 3 by loosening either screw 8^d the members 9, 9^a can be rotatorially adjusted in the tubes 8^c so as to adjust their points toward or from each other and produce a spark gap of the desired extent.

The batteries 2 are connected in series by wire 2^a, and a conductor 2^b leads from the positive terminal of one battery to one terminal 5^a of an interrupter 5, of any suitable construction, the other terminal 5^b of said interrupter is connected by a wire 5^c to the primary coil 3^a of the transformer 3, of any suitable construction, having preferably a metal core 3^b, the other terminal of the primary coil 3^a is connected by a wire 3^c to one pole 7^a of a circuit closer mounted on the igniter casing 8. And from the other pole 7^b of said closer a conductor 2^d leads to the minus terminal of the batteries 2, thus completing a circuit through the transformer primary when the circuit closer is closed. The portions of the several conductors, extending between the casing 1 and the casing 8, are preferably incased in a rubber tube 7^d 110

to protect them and prevent tangling thereof and for convenience in transporting and handling the apparatus.

- One pole of the secondary winding 3^a of the transformer is connected by a wire 3^m to one member of the condenser 4, and the other terminal of the secondary winding 3^a is connected to the wire 3^c, and thereby to the pole 7^a of the circuit closer on the casing 8; and this pole 7^a is also connected by a wire 7^c with the spark member 9^a. The other member of the condenser 4 is also connected by a wire 4^c extending to and through the casing 8 with the other spark member 9. 15 The pole 7^a of the circuit closer is electrically connected with a spring plate 7^e attached to the casing 8 and extending over and normally out of contact with the pole 7^b. This handle 7 may be provided with a finger piece 7ⁿ of insulating material by which it can be depressed, so as to move the spring 7^e into electrical contact with the pole 7^b and close the primary circuit from the batteries through the primary induction coil and interrupter back to the batteries; at the same time an induced circuit is closed from the secondary induction coil through the condenser, and the sparking members 9, 9^a back to the secondary. 25 The primary current is rapidly periodically broken by the interrupter, resulting in the production of a powerful induced current, the voltage of which current is increased by the condenser in the well known manner; and such current passing between the points of the sparking members 9, 9^a will create sparks sufficient to ignite a fuse. When a fuse is ignited the circuit closer is released, stopping the operation of the apparatus. 35

The device is light and easily transported and its efficiency will be readily appreciated by miners and those engaged in blasting operations.

- 45 In use the miner swings the knapsack or casing over his shoulder, or carries it on his back, the circuits normally remaining closed. If desired, and for convenience, an insulating member 10 may be provided on the handle 8 which when the device is being transported can be inserted between the spring 7^a and the pole 7^b.

It is obvious that those skilled in the art may vary the details of construction and arrangement of parts without departing from the spirit of my invention, and therefore I do not wish to be limited to such features except as may be required by the claims.

- 60 What I claim is:

1. In an electrical fuse lighter, a tubular casing or handle, insulating closures, a pair of electrodes or sparking member rotatorially adjustably mounted on said handle, a circuit closer, and conductors connecting

said sparking members or electrodes and said circuit closer, substantially as described.

2. In an electrical fuse lighter, a tubular casing or handle, closures constructed of hard rubber for the respective ends of the 70 casing, a pair of electrodes or sparking members rotatorially adjustably mounted in one of said end closures; a circuit closer mounted on the casing, and conductors extending into the casing and connecting with said 75 sparking members or electrodes and the terminals of said circuit closer, substantially as described.

3. In an electrical fuse lighting apparatus, the combination of a casing, an insulated 80 head, a pair of rotatorially adjustable sparking members mounted in said head having curved outer ends so that the points on the outer ends of said members may be adjusted toward or from each other to form the desired spark gap by rotatorially adjusting 85 said members.

4. In an electrical fuse lighting apparatus, the combination of a casing having an insulated 90 head provided with a projecting rib on its outer end, a pair of tubes mounted in said head on opposite sides of said rib, sparking members mounted in said head and having curved outer ends and rotatorially adjustable so that the points on the outer 95 ends of said head may be adjusted toward or from each other to form the desired spark gap, with means for fastening the sparking members in adjusted position.

5. In an electrical fuse lighter, a casing 100 having an insulated head provided with a projecting rib on its outer end, a pair of sparking members mounted in said head and adjustable to form the desired spark gap; and means for fastening the sparking members in adjusted position. 105

6. In an electrical fuse lighter, a casing having an insulated head, a pair of tubes mounted in said head, sparking members mounted in said tubes and having curved 110 outer ends and adjustable to form the desired spark gap; and means for fastening the sparking members in adjusted position.

7. In an electrical fuse lighter, a casing having an insulated head provided with a projecting rib on its outer end, a pair of tubes mounted in said head, sparking members mounted in said tubes and having curved outer ends and adjustable to form the desired spark gap; and means for fastening the sparking members in adjusted position. 115 120

8. In an electrical fuse lighter wherein a circuit closer, a battery, an interrupter, a transformer, conductors connecting the circuit closer terminals the transformer primary and the interrupter and the battery in circuit, and a condenser are employed; the combination of a casing having an insulated head provided with a projecting rib on its 125 130

outer end, a pair of sparking members mounted in said head and adjustable to form the desired spark gap; and conductors connecting said sparking members, condenser 5 and secondary of the transformer in circuit, substantially as described.

9. In an electrical fuse lighter wherein a circuit closer, a battery, an interrupter, a transformer, a condenser, and conductors 10 connecting the circuit closer terminals the transformer primary and the interrupter and the battery in circuit are employed; the combination of a casing having an insulated head, a pair of tubes mounted in said head, 15 sparking members mounted in said head and adjustable to form the desired spark gap; means for fastening the sparking members in adjusted position; and conductors connecting said sparking members, condenser and secondary of the transformer in circuit, 20 substantially as described.

10. In an electrical fuse lighter wherein a circuit closer, a battery, an interrupter, a transformer, conductors connecting the circuit closer terminals the transformer primary and the interrupter and the battery in circuit, and a condenser are employed; 25 the combination of a casing having an insulated head provided with a projecting rib on its outer end, a pair of tubes mounted in said head, sparking members mounted in said head and having curved outer ends and adjustable to form the desired spark gap; means for fastening the sparking members in adjusted position; and conductors connecting said sparking members, condenser and secondary of the transformer in circuit, 30 substantially as described.

In testimony that I claim the foregoing as my own, I affix my signature.

ALBERT S. COLE.
